APPARATUS FOR THE SUPPLY OF OZONE AND THE LIKE

Filed July 10, 1930

INVENTOR:

Fergus Ferguson

BY Fred F. Barlow

ATTORNEY

UNITED STATES PATENT OFFICE

FERGUS FERGUSON, OF PARIS, FRANCE

APPARATUS FOR THE SUPPLY OF OZONE AND THE LIKE

Application filed July 10, 1930, Serial No. 466,947, and in France April 14, 1930.

The present invention relates to an installation for the supply of ozone for industrial, domestic, medical and other use, for instance amongst others for beauty, dental and mouth treatments and biological studies.

The installation comprises pipes connected to a device in which ozone is produced and a compressor apparatus of any kind, to convey the ozone where required and at a desired pressure.

In order that the invention may be better understood, it will now be described with reference to the accompanying drawings in which:—

15 Fig. 1 shows in elevation an apparatus according to the invention, suitable for fixing on a wall or the like.

Fig. 2 shows a section in side elevation, to a larger scale, of a portion of the apparatus shown in Fig. 1, the actual ozone-producing part being indicated in dotted lines.

Fig. 3 is a view in elevation partly in section of the ozone-producing device indicated in Fig. 2.

25 Fig. 4 is a plan view of one of the supporting discs of the ozone-producing device, and

Fig. 5 shows in elevation a portable apparatus, constructed according to the invention and mounted on wheels.

The ozone-producing apparatus comprises a receptacle A carried by bracket-like devices B and adapted to be hermetically closed by means of a cover J fixed in position by bolts L. The cover has a central orifice provided with a cock K permitting the receptacle A to be connected to a manometer. The receptacle further comprises a lateral orifice E for the admission of the air under pressure and an orifice F in the base adapted to have connected thereto a pipe or the like for the distribution of the ozone produced.

Two threaded rods D mounted in ebonite blocks C are provided to act as conductors for

the current and these are connected to the output terminals of a Ruhmkorff coil D'.

The actual ozone-producing device, which is adapted to be housed in the receptacle A, is constituted by an aluminium disc I forming the positive pole and connected electrically to one of the threaded rods D by means of a strip or laminated contact and by a second disc I' also of aluminium connected to the lower threaded rod D and forming the negative pole. These discs are interconnected by an ebonite rod or spindle H and each is pierced with eight holes O in which are mounted glass tubes M.

Each glass tube M is surrounded by a helically coiled aluminium wire N which contacts with the upper disc I whilst the interior of each tube has located therein a twisted flattened strip or wire N' of copper or aluminium which contacts with the lower disc I'.

The device thus constituted is introduced into the receptacle A, a handle or the like V formed with two branches facilitating its insertion.

When a difference of potential is established between the armatures thus formed by connecting them to the poles of a Ruhmkorff coil D' and after a certain quantity of air under pressure has been introduced into the receptacle A, then this air is ozonized at the end of a determined period of time.

Piping connected to the orifice F allows the ozonized air to be brought to any desired place and at the required pressure, which may be regulated at will.

According to Fig. 1, the receptacle A is mounted on a board by suitable connecting means. The Ruhmkorff coils D' and D'' are provided connected to the actual ozonizing device represented in Fig. 3. I is the switch and E the middle portion of a passage for the ozone from the receptacle A to a distributor F, provided with three or more cocks G for the distribution of ozonized air. The

ocks G are adapted to be connected to pipes leading to positions in which the ozone is to be utilized. A glass receptacle R may be employed for the sterilization of water by the 5 ozone.

The wall apparatus just described is described for dental or medical service with the object of using the ozonized air as a disinfectant and antiseptic medium.

- 10 Fig. 5 shows a complete apparatus constructed according to the invention mounted upon a trolley and especially suitable for use in a hospital or the like. In this method of carrying the invention into effect, 1 represents a receiver or reservoir for compressed air mounted upon castors. The compressed air is supplied by a small piston compressor 2 operated by an electric motor 3. On a table or support 4 fixed to the cover of the reservoir 1 the receptacle A is mounted, the interior of the receptacle having therein the ozone-producing device shown in Fig. 3. Piping 5, with cocks 6 and 7, allows the ozonized air to be brought into a receptacle 8 filled with water by means of a plunger tube 9 fixed in the cover 11, so as to bubble through the water in the receptacle to assure its perfect sterilization. A cock 10 is provided for drawing off the water thus sterilized. The cover 11 forms at the same time a distributor for ozonized air and with this object is provided with two lateral cocks 12 which are adapted to be connected to rubber pipes or the like for conveying the ozonized air to 35 the desired positions.

The methods of carrying the invention into effect particularly described are given by way of example only. The compressed air may be supplied by means of a small compressor and the apparatus described would then be connected to the receiver of the compressor or even could be located in the interior thereof if desired.

The present invention is further applicable 45 to all cases for the supply of ozone or ozonized air under pressure, whatever the precise form of the actual ozone-producing apparatus and can be utilized as a wall apparatus as has been hereinbefore described or coupled 50 with any fixed or movable suitable compressor apparatus.

What I claim and desire to secure by Letters Patent of the United States of America is:—

- 55 1. An apparatus for producing and supplying ozone or ozonized air for medical, dental and other purposes, comprising a receptacle with one open end, a cover for said open end, means for clamping the cover in position over the open end to secure an hermetic seal, supporting means for said receptacle, an insulated electrical conductor passing from the exterior to the interior of the receptacle, another insulated electrical conductor passing from the exterior to the interior of the receptacle, 60

receptacle and spaced from the first-mentioned insulated electrical conductor, a Ruhmkorff coil carried by the said supporting means, connections between the output terminals of the Ruhmkorff coil and the two said electrical conductors, a plurality of glass tubes located in the receptacle, a disc of aluminium adapted to be located in the receptacle and to be electrically connected to one of the electrical conductors, another similar disc of aluminium adapted to be located in the receptacle and electrically connected to the other conductor, a spacing rod of ebonite connecting the two said aluminium discs, a plurality of apertures in each of said aluminium discs for the reception of the plurality of glass tubes, a helically coiled aluminium wire surrounding each of said tubes, and electrically connected to one of the aluminium discs, a twisted strip of copper in each of the said tubes and electrically connected to the other of the said aluminium discs, an inlet for compressed air to the interior of the receptacle, an outlet for ozone or ozonized air from the receptacle, a piping system in connection with the said outlet, a plunger tube in connection with said piping system, and a receptacle for liquid into which the said plunger tube is adapted to project from above, for the purposes set forth.

2. An apparatus for producing and supplying ozone or ozonized air for medical, dental and other purposes, comprising a receptacle with one open end, a cover for said open end, means for clamping the cover in position over the open end to secure an hermetic seal, supporting means for said receptacle, an insulated electrical conductor passing from the exterior to the interior of the receptacle, another insulated electrical conductor passing from the exterior to the interior of the receptacle and spaced from the first-mentioned insulated electrical conductor, a Ruhmkorff coil carried by the said supporting means, connections between the output terminals of the Ruhmkorff coil and the two said electrical conductors, a plurality of glass tubes located in the receptacle, a disc of aluminium adapted to be located in the receptacle and to be electrically connected to one of the electrical conductors, another similar disc of aluminium adapted to be located in the receptacle and electrically connected to the other conductor, a spacing rod of ebonite connecting the two said aluminium discs, a plurality of apertures in each of said aluminium discs for the reception of the plurality of glass tubes, a helically coiled aluminium wire surrounding each of said tubes and electrically connected to one of the aluminium discs, a twisted strip of copper in each of the said tubes and electrically connected to the other of the said aluminium discs, a reservoir for compressed air, supporting wheels to the said reservoir, the said reservoir carrying the means supporting the open-ended receptacle 1

and associated parts, a compressor carried by the reservoir for supplying compressed air thereto, an electric motor operatively connected with the said compressor, an inlet for compressed air to the interior of the receptacle, a connection between the reservoir and the said inlet, an outlet for ozone or ozonized air from the receptacle, a piping system in connection with the said outlet, a plunger tube in connection with said piping system, and a receptacle for liquid into which the said plunger tube is adapted to project from above, for the purposes set forth.

In witness whereof I affix my signature.

F. FERGUSON.
